PAGE-END INDICATOR FOR TYPEWRITERS

George G. Knieriem, Jr., Long Beach, Miss.

Application September 2, 1949, Serial No. 113,687

4 Claims. (Cl. 197—189)

1

This invention relates to typewriter indicator attachments, and more particularly to an attachment for indicating the proximity of the end of a sheet or the proximity of a predetermined point on the sheet during typing, and which provides an audible signal denoting that the end of the sheet or said predetermined point on the sheet has been reached.

A main object of the invention is to provide a novel and improved page-end indicator for typewriters, said indicator being very simple in construction, easy to install on a typewriter, and very easy to adjust to provide the desired indication.

A further object of the invention is to provide an improved indicating attachment for typewriters which is very inexpensive to manufacture, which is compact in size, which is reliable in operation, and which provides an audible signal when a predetermined length of the typewritten sheet has been fed through the typewriter.

Further objects and advantages of the invention will become apparent from the following description and claims, and from the accompanying drawings, wherein:

Figure 1 is a top plan view of the side portion of a typewriter provided with a page-end indicating attachment constructed in accordance with the present invention;

Figure 2 is a fragmentary front elevational view of the typewriter of Figure 1, showing the attachment in front elevation, a portion of the attachment being broken away;

Figure 3 is an enlarged cross-sectional detail view taken on line 3—3 of Figure 2;

Figure 4 is a cross-sectional detail view taken on line 4—4 of Figure 3;

Figure 5 is an enlarged cross-sectional detail view taken on line 5—5 of Figure 3;

Figure 6 is an enlarged cross-sectional detail view taken on line 6—6 of Figure 3;

Figure 7 is an enlarged perspective detail view of the signal-release cam member employed in the typewriter attachment of Figure 1.

Referring to the drawings, 11 designates a conventional typewriter, and 12 designates the right end of the roller shaft of the typewriter. The page-end indicator device is indicated generally at 13.

The indicator device comprises a rectangular housing 14 which has end walls 15 and 16, side walls 17 and 18, a top wall 19, and an intermediate partition wall 20 extending parallel to the side walls 17 and 18, as shown in Figure 3.

Mounted on the inner side wall 18 is a bell 21. Rotatably mounted in the lower marginal portions of the end walls 15 and 16 between the walls 17 and 20 is a shaft 22 formed with a worm portion 23. The inner end of shaft 22 has

2

secured thereto a sleeve 24 which is telescoped over and secured to the end of the roller shaft 12, as by a set screw 25. Secured to the outer end of shaft 22 is the roller knob 26. The housing 14 is secured to the frame of the typewriter 11 in any suitable manner.

Designated at 27 is a sleeve member which extends rotatably through the intermediate wall member 20, said sleeve member being rotatably supported in respective bearing sleeves 28 and 29 secured to said wall member 20. At one end thereof sleeve 27 is formed with an annular flange 30 which rotatably engages the end of sleeve 28. Secured to the other end of sleeve 27 is a gear 31 which meshes with the worm portion 23 of shaft 22. The wall 17 is formed with a large circular aperture 32 having the same axis as sleeve 27, and disposed rotatably in said aperture is a disc 33 which is rigidly secured in parallel relationship to gear 31 by a plurality of bar elements 34 extending from the periphery of disc 33 parallel to the axis thereof and secured to the gear 31. Secured axially to gear 31 facing disc 33 is a centrally-apertured drum 35 formed with a peripheral notch 36.

Extending rotatably and slidably through wall 18, sleeve 27, gear 31, drum 35 and disc 33 is a shaft 37. At its left end, as viewed in Figure 3, an enlarged head member 38 is secured to shaft 37, limiting movement of said shaft to the right. Head member 38 is normally in frictional engagement with a friction disc 57 secured to the wall 18 around the shaft 37, as shown in Figure 3. Secured to the shaft 37 inwardly of wall 18 is an enlarged washer 39. A coiled spring 40 encircles shaft 37 and bears between washer 39 and flange 30, biasing shaft 37 to the left, as viewed in Figure 3. Secured to shaft 37 adjacent drum 35 is a disc 41 formed at its periphery with a projection 42 which normally engages the peripheral edge of drum 35 and holds the shaft against endwise movement to the left until it engages in the notch 36, at which time the shaft is released for movement to the left by the expansion of spring 40.

Pivoted at 43 to wall 18 is a lever 44 whose outer end projects through an opening 45 formed in said wall, and carries a striker or hammer 46 disposed adjacent bell 21. The inner end of lever 44 is formed with spaced lugs 47 and 48 between which the washer 39 is normally disposed. When the shaft 37 is moved to the left by the entry of lug 42 into notch 36, as above described, washer 39 moves over lug 47, rocking lever 44 clockwise, as viewed in Figure 3, and causing hammer 46 to strike bell 21.

Mounted on the outer end of shaft 37 is a ratchet knob 49. Knob 49 is rotatably mounted on a sleeve race member 50 splined to shaft 37 carrying balls 51 which engage in respective spiral recesses 52 formed inside the knob 49. When the

knob 49 is rotated clockwise, as viewed in Figure 5, the spiral recesses 52 cooperate wedgingly with the balls 51 and sleeve race 50 to rotate shaft 37 clockwise. Rotation of knob 49 counterclockwise produces no rotation of shaft 37.

Shaft 37 is formed adjacent sleeve race 50 with a longitudinal slot 53 in which is transversely positioned a pointer bar 54. A coiled spring 55 encircles shaft 37 and bears between pointer bar 54 and the end of sleeve race 50, biasing bar 54 against the left end of slot 53, as viewed in Figure 3.

The outer surface of disc 33 is marked with a scale 56 which may be suitably calibrated, for example, in inches of circumferential length of the typewriter roller.

In setting the device at the beginning of a page, the pointer 54 is initially at zero position with respect to scale 56 and lug 42 is located in notch 36. The operator places the paper in the typewriter, lines the paper up at the desired starting point, then pulls knob 49 outwardly to remove lug 42 from notch 36, and then rotates knob 49 clockwise, as viewed in Figure 2, to set the pointer bar 54 to the number of inches corresponding to the number of lines to be typed on the sheet. This places lug 42 at a point on the rim of drum 35 spaced from notch 36 in accordance with the number of revolutions of the roller of the typewriter required to move the paper to a position corresponding to the last typewritten line desired on the sheet. The typist proceeds with the typing operation. When the last-desired line is reached on the paper, the lug 42 slips into notch 36, causing the hammer 48 to strike bell 21, as above described. At the same time, the pointer 54 indicates zero on the scale, 56. The typist is thus provided with both a visual and an audible indication that the last line on the sheet has been reached.

When lug 42 is in engagement with the rim of drum 35, head 38 frictionally engages the friction disc 57 and prevents shaft 37 from rotating with gear 31. The friction between head 38 and disc 57 is insufficient, however, to prevent shaft 37 from being rotated manually by knob 49 in setting the indicator device.

While a specific embodiment of a page-end indicator for typewriters has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a typewriter, a paper-feeding roller provided with a shaft, a housing secured to the frame of the typewriter at one side thereof adjacent said shaft, a worm element journaled in said housing and connected to said shaft, a gear rotatably mounted in said housing and meshing with said worm element, a disc secured axially to said gear and extending through a wall of the housing, said disc being provided with a calibrated scale, a rod element rotatably carried in said housing and extending rotatably through the center of said gear and said disc, a pointer carried by said rod element extending adjacent said scale, and interengaging friction means carried by said rod element and said housing normally holding said rod element against rotation with respect to the housing.

2. In a typewriter, a paper-feeding roller pro-

vided with a shaft, a housing secured to the frame of the typewriter at one side thereof adjacent said shaft, a worm element journaled in said housing and connected to said shaft, a gear rotatably mounted in said housing and meshing with said worm element, a disc secured axially to said gear and extending through a wall of the housing, said disc being provided with a calibrated scale, a rod element rotatably carried in said housing and extending rotatably through the center of said gear and said disc, a pointer carried by said rod element extending adjacent said scale, interengaging friction means carried by said rod element and said housing normally holding said rod element against rotation with respect to the housing, a peripherally-notched drum secured axially to said gear, a projection carried by said rod element engaging the rim of said drum, spring means biasing the rod element axially in a direction to urge the projection into the notch of the drum, and audible signal means operated in response to the entry of said projection in the notch.

3. In a typewriter, a paper-feeding roller provided with a shaft, a housing secured to the frame of the typewriter at one side thereof adjacent said shaft, a member rotatably mounted in said housing, means coupling said member to the typewriter shaft, a disc secured axially to said member and extending through a wall of the housing, said disc being provided with a calibrated scale, a rod element rotatably carried in said housing and extending rotatably through said member and said disc, a pointer carried by said rod element extending adjacent said scale, and interengaging friction means carried by said rod element and said housing normally holding said rod element against rotation with respect to the housing.

4. In a typewriter, a paper-feeding roller provided with a shaft, a housing secured to the frame of the typewriter at one side thereof adjacent said shaft, a member rotatably mounted in said housing, means coupling said member to the typewriter shaft, a disc secured axially to said member and extending through a wall of the housing, said disc being provided with a calibrated scale, a rod element rotatably carried in said housing and extending rotatably through the center of said member and said disc, a pointer carried by said rod element extending adjacent said scale, interengaging friction means carried by said rod element and said housing normally holding said rod element against rotation with respect to the housing, a peripherally-notched drum secured axially to said member, a projection carried by said rod element engaging the rim of said drum, spring means biasing the rod element axially in a direction to urge the projection into the notch of the drum, and audible signal means operated in response to the entry of said projection in the notch.
